UNITED STATES PATENT OFFICE.

ARTHUR A. WALTERS, OF SANDUSKY, OHIO.

GRATE.

1,179,245.

Specification of Letters Patent.

Patented Apr. 11, 1916.

Application filed June 12, 1915. Serial No. 33,734.

To all whom it may concern:

Be it known that I, ARTHUR A. WALTERS, a citizen of the United States, residing at Sandusky, in the county of Erie and State 5 of Ohio, have invented new and useful Improvements in Grates, of which the following is a specification.

The invention relates to draft creating devices for fire boxes in stoves or the like, and 10 more particularly to the class of draft conducting grates for stoves or the like.

The primary object of the invention is the provision of a grate of this character wherein slack coal can be used as fuel, and 15 air will be admitted throughout the entire mass thereof when supported by the grate so as to assure complete and perfect combustion of the fuel without possibility of the puffing or the smoking of the fuel resulting 20 from irregular combustion within the stove.

Another object of the invention is the provision of a grate of this character wherein the slack coal by reason of the maximum 25 draft will be caused to glow continuously, thereby giving forth constant heat and assuring complete combustion.

A further object of the invention is the provision of a grate of this character which 30 is simple in construction, novel in form, thoroughly reliable and efficient in its purpose, strong, durable, and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawing:—Figure 1 is a vertical longitudinal sectional view through a stove and grate constructed in accordance with the invention. Fig. 2 is a plan view of the holder for the grate. Fig. 3 is a plan view of the grate. Fig. 4 is a sectional view on the line 4—4 of Fig. 1.

Similar reference characters indicate corresponding parts throughout the several views in the drawing.

45 Referring to the drawings in detail, A designates a portion of the body of a heating stove, which is of the ordinary well-known construction, having a downwardly tapered fire box B which communicates with 50 an ash pit C formed in the base D of the body of the stove, and this base is supported

upon legs E of the ordinary well-known construction for elevating the body of the stove from the foundation or flooring.

Arranged within the fire-box B is a grate 60 holder comprising a ring or annulus 5 which is formed with an outer beveled periphery 6 corresponding to the inner tapering diameter of the fire box B so as to snugly fit within the same, and integral with and extending from two points at the rearmost portion of the ring or annulus 5 are forwardly converging supporting arms 7 which merge with each other at their free ends, at which point there is formed an upstanding lug 8 for engagement with a grate hereinafter fully described.

The grate comprises a disk 9 having a central opening 10 and a plurality of radially disposed slots 11 concentrically disposed with respect to the said central opening 10, while at the periphery of this disk 9 at intervals are the series of protuberances 12, and this disk is adapted to rest upon the arms 7 of the holder when the grate is 80 placed within a stove. Rising above the central opening 10 in the disk 9, and riveted concentrically about the same is the outwardly annular flange 13 of a hollow conical shaped column 14 having a plurality of perforations 15 in staggered relation to each other therein, and this column 14 serves as an air conductor for distributing the draft within the stove throughout the mass of fuel held upon the grate. The slots 11 and the 85 spaces between the protuberances 12 also afford air openings for admitting the draft through the bed of the fuel when supported upon the grate and filling the fire box B interiorly of the stove.

90 The disk 9 constituting the grate is formed with an opening 16 which is adapted to receive the lug 8 on the arm 7 of the grate holder so as to hold the disk firmly thereon, while at the periphery of the disk 9 is a 100 handle 17 which extends without the body A of the stove through a suitable elongated opening or slot 18, and by manipulating this handle the disk can be partly turned or reciprocated for the shaking of the grate.

105 It will be noted that maximum air will be admitted through the column to the mass of fuel for the complete and perfect combustion thereof, and especially when using slack coal, which is dumped upon the grate 110 in the usual well-known manner.

From the foregoing description, taken in

connection with the accompanying drawing, the construction and manner of operation of the device will be clearly understood, and therefore a more extended explanation has 5 been omitted.

What is claimed is:—

A grate holder comprising an annulus having a downwardly-converging edge wall to be held within and in contact with a 10 downwardly convergent wall forming the fire box, arms projected from said annulus in spaced relation and converging, said arms meeting at a point beyond the center of the annulus, the juncture of the arms being pro-

vided with an upstanding lug, the arms and 15 lug being between the planes of the upper and lower edges of the annulus, and a disk-like grate mounted for sliding and rotary movement on the lug, and of a diameter materially less than the same dimension of the 20 annulus.

In testimony whereof I affix my signature in presence of two witnesses.

ARTHUR A. WALTERS.
